UNITED STATES PATENT OFFICE.

JAMES BRADY, OF BROOKLYN, NEW YORK, ASSIGNOR TO CHEEVER K. DODGE, OF SAME PLACE.

MACHINERY FOR STRETCHING LEATHER BELTING.

SPECIFICATION forming part of Reissued Letters Patent No. 9,059, dated January 27, 1880.

Original No. 191,920, dated June 12, 1877. Application for Reissue filed December 4, 1879.

To all whom it may concern:

Be it known that I, JAMES BRADY, of Brooklyn, in the county of Kings and State of New York, have invented certain new and useful Improvements in the Process of and Machines for Stretching Leather Belting; and I hereby declare that the following is a full, clear, and exact description of the same, reference being had to the accompanying drawings, forming part of this specification.

My invention supplies a much-desired means for permanently stretching leather belting, before using the same, in a much more thorough and uniform manner than has yet been accomplished.

When leather belting is stretched by longitudinal stress in any common apparatus for generating such stress by pulling in opposite directions upon the ends of the belting, the belting permanently stretches almost wholly in its weaker parts, and the stronger parts, when the belt is subsequently used on pulleys, stretch still farther, and the belt becomes slack. In searching for the cause of such stretching on the pulleys, which takes place notwithstanding the longitudinal strain of the belt on the pulleys may be less than the belt has been subjected to in the previous stretching process, I have found that the stretching

on the pulleys is caused principally by the alternate bending and straightening successively of all parts of the belts, respectively, at points which come in contact with and leave the surface of the pulleys when the belt is running. This alternate bending and straightening of the belt in its various parts act to force the fibers of its texture over one another, and therefore act to stretch the stronger parts of the belt as well as the weaker.

My invention consists in the combination, in a machine for stretching leather belting, of a delivery-roller upon which the belt is rolled and from which it is drawn, a brake for retarding the motion of said delivery-roller, and a receiving-roller upon which the belt is rolled as it is drawn from said delivery-roller.

In order to increase the flexure of the belt as it is passed from one roller to the other, I preferably arrange between said rollers one or

more flexion and reflexion rollers, over which the belt is passed, and certain of these flexion and reflexion rollers may be supported in adjustable bearings.

Figure 1 in the accompanying drawings is a top view of a machine for stretching belting constructed in accordance with my invention. Fig. 2 is a vertical section of the same on the line *xx* in Fig. 1.

A is the frame of the machine, at opposite ends of which are, respectively, placed a delivery-roll, *B*, and a receiving-roll, *B'*, the belting *D* to be stretched being wound first upon said delivery-roll and onto said receiving-roll during the process of stretching said belting. In passing from one roller to the other the belt is subjected to flexure in the same manner as when in use.

The amount of flexure to which the belt is subjected may with advantage be increased by arranging between the delivery-roller *B* and the receiving-roller *B'* one or more flexion-rollers, over which the belt passes in its passage from the roller *B* to the roller *B'*.

I have here represented a series of flexion and reflexion rollers, *E E'*, over and under which the belt passes, and the rollers *E'* are shown as supported in adjustable bearings in the frame *A*.

The delivery-roll *B* and the receiving-roll *B'* are each provided with a fixed flange or head, *C*, and an adjustable flange or head, *C'*, which confine the belt laterally when undergoing the stretching process and keep it straight, the adjustable flange *C'* being provided with a set-screw or other means for holding it in position. Means for attaching the ends of the belting, respectively, to said delivery and receiving rolls are also provided, a groove, *g*, in which the end of the belt is inserted and clamped by wedging or otherwise, being advantageously employed for this purpose.

The said flexion and reflexion rollers *E* and *E'* are here shown as placed in parallel relation with each other and the rolls *B* and *B'*; but I do not limit myself to any particular number or position of said rollers between the rolls *B* and *B'*.

To the frame A is pivoted the weighted lever-brake F, which, in use, bears against the coil of belting wound on the delivery-roll B; but I do not limit myself to a weighted lever-brake, nor to any particular construction of the brake.

By causing the brake to bear against the coil of belting I oppose its frictional resistance to a constantly-diminishing radius, and 10 the leverage of said resistance is decreased exactly as the leverage of the belting upon the delivery-roll is decreased, making constant the tension under which the belting is wound off from the said delivery-roll; but the brake may be 15 otherwise constructed and applied to give the required constant tension to the belting. The adjustability of the flexion and reflexion rolls E' adapts the machine to stretching long or short belts.

20 The belting D to be stretched is first attached to and wound upon the delivery-roll B, and the brake F is applied thereto. The free end of the belting is then passed alternately over the several flexion and reflexion rollers E and under the adjustable flexion and reflexion rollers E', and attached to the receiving-roll B'. Power is then applied to effect the turning of the said receiving-roll and unwind the belt from the delivery-roll. In passing from the 25 delivery-roll to the receiving-roll all parts of the belting are subjected to alternate and repeated flexion and reflexion while under longi-

tudinal strain, and the thorough permanent stretching of the thicker as well as the thinner parts of the belting is effected.

What I claim as my invention, and desire to secure by Letters Patent, is—

1. In a machine for stretching leather belting, the combination of a delivery-roller upon which the belt is rolled and from which it is 40 drawn, a brake for retarding the motion of said delivery-roller, and a receiving-roller upon which the belt is rolled as it is drawn from said delivery-roller, substantially as specified.

2. In a machine for stretching leather belting, the combination of a delivery-roller upon which the belt is rolled and from which it is drawn, a brake for retarding the motion of 45 said delivery-roller, a receiving-roller upon which the belt is rolled as it is drawn from said delivery-roller, and one or more flexion-rollers over which the belt passes in its passage from the delivery-roller to the receiving-roller, substantially as specified.

3. The combination of the delivery-roller B, 55 the receiving-roller B', the flexion and reflexion rollers E, the flexion and reflexion rollers E', supported in adjustable bearings, and the brake F, substantially as specified.

JAMES BRADY.
